UNITED STATES PATENT OFFICE.

NORA NEWELL, OF NEW YORK, N. Y.

DESIGN FOR A PICTURE OR PHOTOGRAPH FRAME.

51,286.

Specification for Design. Patented Sept. 18, 1917.

Application filed May 26, 1917. Serial No. 171,325. Term of patent $3\frac{1}{2}$ years.

To all whom it may concern:

Be it known that I, NORA NEWELL, a citizen of the United States, residing at New York city, in the county of New York and State of New York, have invented a new, original, and ornamental Design for a Picture or Photograph Frame, of which the following is a specification, reference being had to the accompanying drawing, forming part thereof.

The figure is a face view of a picture or photograph frame embodying my design.

I claim:

The ornamental design for a picture or photograph frame, as shown.

NORA NEWELL.

Witnesses:

ROBERT P. KNAPP,

WILLIAM BANTA.
